Geo H. Felt

UNITED STATES PATENT OFFICE.

GEORGE H. FELT, OF NEW YORK, N. Y.

IMPROVEMENT IN SIGNAL-ROCKETS.

Specification forming part of Letters Patent No. 39,636, dated August 25, 1863; antedated July 29, 1863.

To all whom it may concern:

Be it known that I, GEORGE H. FELT, of the city, county, and State of New York, have invented a certain new and useful Improvement in Rockets; and I do hereby declare that the following is a full, clear, and exact description of the same, reference being had to the accompanying drawings, forming part of this specification.

This invention is more especially designed for signal-rockets for military and other operations.

It consists, first, in the application to or within a rocket of a Roman candle for the purpose of discharging stars of the same or different colors one after the other, and thereby enabling a greater variety of and more distinct signals to be produced.

It consists, secondly, in making the stars of the Roman candle with cavities in their upper ends containing charges of gunpowder or other suitable explosive substance for the purpose of driving out the balls from the case and igniting them at the same time.

It consists, thirdly, in so combining a balloon with a rocket as to make it keep suspended for a time or retard the descent of a Roman candle or other fire-work discharged from the rocket for the purpose of making a signal, whereby such fire-work is rendered visible for a longer period and the signal enabled to be better understood than if it descended quickly.

It consists, fourthly, in the novel construction and arrangement of a series of divergent spiral passages in the bottom of the rocket, for the purpose of obtaining its rotary motion by the escape of the gases eliminated in the combustion of the charge, and thereby dispensing with the stick heretofore commonly used to guide and steady the flight of the rocket.

Figure 1 in the drawings is a central longitudinal section of a rocket having a Roman candle applied within it. Fig. 2 is a similar section on a smaller scale, exhibiting the application of the balloon in combination with the Roman candle. Fig. 3 is a longitudinal view of the plug which forms the bottom of the rocket-case, illustrating my improved construction and arrangement of the spiral pas-

sages. Fig. 4 is a view of the lower end of said plug. Fig. 5 is a longitudinal section of the fuse which I employ in connection with my rockets.

Similar letters of reference indicate corresponding parts in the several figures.

A is an inner case of paper, and B an outer case of gutta-percha or india-rubber combined to form a water-proof case for the rocket. This case is made long enough to contain the Roman candle, and when no balloon is to be used it is closed at the top by a cap, C, of hard vulcanized gutta-percha or india-rubber, as shown in Fig. 1; but when the balloon is to be used it has screwed onto it or otherwise attached to it a case, D, for containing the balloon E, as shown in Fig. 2, and the cap C is put on the balloon-case D.

F is the case of the Roman candle, made of hard vulcanized india-rubber or gutta-percha, fitted snugly into the case A B. This case A B is open at the bottom and closed at the top, and the stars *a a b b c c* may be of one color, or of two or more different colors, the different colors being arranged one above the other or side by side, as shown in Figs. 1 and 2, according to the combinations required to produce the signals, the different colors being arranged side by side, as illustrated by *b b*, or one above the other, as illustrated by *c c*, to be fixed simultaneously, each star with a quantity of rocket composition, *d*, by which the proper intervals between the discharge of the several stars is regulated and a quantity of gunpowder or other explosive material, *e*, to produce the discharge and ignition of the stars, being put into a tin-foil case, *f*, represented in blue color in Figs. 1 and 2, ready for placing in the case F, thereby affording convenience for making any variety of combinations in the Roman candle. Each star is made with a cup-like concavity in its upper end, as shown in Figs. 1 and 2, to contain its respective charge of gunpowder, *e*, which obviates the necessity of putting it in a separate package, and is therefore very convenient.

One, two, or more stars, with their respective quantities of rocket-composition *b* and gunpowder *e* inclosed in the tin-foil cases *f*, may be put into cases *g g* of vulcanized india-rubber or gutta-percha, fitted to the interior of

the case F, the said cases *g g* being open at both ends. The use of such cases *g g* affords convenience for varying the combinations, each of such cases being marked to denote the combination and arrangement of the color.

h is the charge of the rocket, made of the usual composition, and put in the case A B in the usual manner, the case being filled up to the fixed diaphragm *i* of gutta-percha or other suitable material. Above this diaphragm is placed the charge of gunpowder *j*, by which the whole Roman candle, including its case F, is discharged from the rocket. As the charge *h* burns out and the rocket has reached the desired elevation, the fire reaches the gunpowder *j* through the vents 7 7, provided in the diaphragm *i*, and the explosion of the said gunpowder drives out the Roman candle in an upward direction from the rocket-case A B, forcing off the cap C, which has only just been fitted tight enough to hold it in place until the Roman candle is required to be driven out. The Roman candle when discharged from the rocket burns like an ordinary Roman candle, the composition *d* being first ignited and the fire from the composition reaching the gunpowder *e* through vents 8 8, provided in the star, and the gunpowder *e* blowing out the star from the cases *g* and F and igniting it and the several stars, being in this way ignited and discharged in succession.

The application of the Roman candle to the rocket produces a different effect from that produced by other rockets—viz., the successive discharge and exhibition of stars of the same or different colors, other rockets discharging and exhibiting all their stars at once, and hence its value for signaling purposes.

The Roman candle is applied to the rocket in the same manner, whether the balloon E is or is not used. The balloon is composed of elastic india-rubber or other flexible material. Before being placed in the case D it is placed in a separate inner case formed of several pieces. The case represented is formed of four pieces, C H H I, of which the cap C forms one. The pieces H H are of hollow semi-cylindrical form, meeting in lines *l*, Fig. 2, fitting to the case D. The said pieces have at their upper ends internal flanges *n n*, to retain within them the bottom piece, I. The said pieces H H may be of hard vulcanized india-rubber or gutta-percha and the bottom piece, I, of wood. The neck of the balloon has connected with it a piece of india-rubber tubing, *p*, which passes through the bottom piece, I, and is fitted with a valve, *g*, opening only in an inward direction. The balloon, after having been put into its inner case, C H H I, and after the said case has been inserted into the outer case, D, from the upper end as far as permitted by the shoulder *r* on the cap C, is charged with hydrogen or other gas at a very high pressure by a suitable pump or other apparatus connected with the tube *p*, and when

this has been done it is connected by a wire, *s*, with the Roman candle, and the case D is screwed onto the rocket. When the charge of the rocket has burned out, the discharge of the Roman candle from the rocket-case takes place, as hereinbefore described, and the Roman candle, pressing upon the bottom I of the inner balloon-case, forces the said case upward through the outer case, D, the Roman candle also passing through the said case, and as soon as the inner case has left the outer one, D, the balloon, being no longer confined, is distended by the great pressure of gas within it, forcing apart the loose side pieces, H H, which fall away from the cap C and leave that free to fall, also leaving the Roman candle suspended from the balloon, which, according to its capacity, may carry the candle still higher, merely keep it suspended at the same elevation, or only retard its descent. The candle suspended from the balloon burns in the same manner as hereinbefore described.

A case made of several pieces on the same principle as C H H I may be used advantageously to contain a parachute for retarding the descent of the Roman candle or other fire-work used in connection with a rocket.

The balloon may be used in combination with a rocket, as above described, for suspending other fire-works than Roman candles—for instance, combustible substances or compounds for producing smoke of different colors for day signals.

The plug J, shown in Figs. 3 and 4, intended as a substitute for a stick, is to be generally employed in connection with a metal rocket-case. It is itself made of brass or other metal, and may be screwed or otherwise secured into the bottom of the case. It is made with any convenient number of spirally-arranged tubes, *u u*, diverging from a central passage, *t*, in a downward or rearward direction. The central passage may or may not be continued through the rear of the plug. The rocket is fired at the central passage, *t*, or at either of all of the spiral passages *u u*, and the fire and gases issuing from its divergent spiral passages or tubes *u u*, besides aiding the issue from the central passage in propelling, produces its rotary about its axis, and so serves to steady and guide it in its flight.

The fuse which I employ in connection with this rocket (represented in Fig. 5) is composed of a piece of ordinary fuse or slow match, *v*, a portion of which is placed loosely in a vulcanized india rubber tube, *w*, and a portion, *x*, embedded in unvulcanized gutta-percha *y*. This fuse is applied to the rocket with the portion *x* outside, and on its end being lighted the said portion burns slowly, and thus provides for the safety of the person firing it; but after this portion has all burned the portion *x* the portion *v* burns through instantaneously and conveys the fire to the charge of the rocket. Similar fuse may be used for shells or other projectiles.

What I claim as my invention, and desire to secure by Letters Patent, is—

1. The combination of the Roman candle with the rocket substantially as and for the purpose herein specified.

2. The construction of the stars of the Roman candle with cup-like concavities for the reception of the charges *e* of gunpowder, by which they are to be discharged from the case of the candle, substantially as and for the purpose herein specified.

3. The combination of a balloon with a

rocket, substantially as and for the purpose herein specified.

4. Though I do not claim constructing a rocket-case with spirally-arranged openings for the escape of the fire and gases to produce a rotary motion, the plug *J*, with its central passage, *t*, and spiral tubes or passages *u u*, combined as and for the purpose herein specified.
